LEAF INSERTING DEVICE

Roger L. Connor and Donald A. Nevin, Athens,
Ohio, assignors to The McBee Company,
Athens, Ohio, a corporation of Ohio

Application July 9, 1935, Serial No. 30,428

7 Claims. (Cl. 129—1)

Our invention relates to peg bars such as are described in the application, Serial No. 10,131, filed March 9, 1935, and relates more specifically to the multiple post bars, which are used on such 5 boards to conveniently support the sheets of paper, which for the convenience and visibility are generally arranged in shingled relation.

In structures of this kind, when the sheets of paper are moved from the peg board, they must 10 be separately filed, and then when again wanted for use on the peg board must be rearranged in the required position.

The principal object of our invention is to provide members for holding the sheets so that the 15 entire number of sheets may be removed simultaneously from the loose leaf binder or file back to a peg bar, without disturbing the arrangement of the leaves in the manner to avoid the present laborious method of handling the sheets one at a 20 time which is required with the use of the peg boards at present employed.

A further object of our invention is to provide means which will permit of the quick transfer of the sheets from one loose leaf binder to another, without disturbing the overlapped or 25 shingled arrangement of the sheets.

A further object of our invention is to provide means which will facilitate the transferring of one set of records from one location to another 30 without having to transfer the entire loose leaf binder or file and yet at the same time will hold the sheets in their prearranged order.

A further object is to provide a multiple post transfer device comprising an upper bar and lower bar which when manually held at both ends 35 may be attached (or detached) one to the other without removing the hands.

Our means of accomplishing the foregoing objects may be more readily understood by having 40 reference to the accompanying drawings which are hereunto annexed and are a part of this specification, in which—

Fig. 1 is a fragmentary plan view of an assembled leaf inserter or transfer device and loose 45 leaf binder;

Fig. 2 is a similar view with the upper clamping means removed;

Fig. 3 shows the assembled transfer device removed from the binder;

50 Figs. 4 and 5 are detail views of the bottom bar; Figs. 6 and 7 are detail views of the top bar; Fig. 8 is a view of the assembled bars;

Fig. 9 is an enlarged detail view partly in section, showing a fastening device for the two bars 55 of the transfer device;

Fig. 10 is an end elevation showing the hinge and prong arrangement of loose leaf binders to which our invention is applied as illustrated in Figs. 1 and 2; and

Fig. 11 is a fragmentary detail view of a modified form of construction. Similar reference numerals refer to similar parts throughout the entire description. 5

As shown in Figs. 1 and 2 we have illustrated a common form of prong loose leaf binder though 10 it will be obvious from the hereinafter contained description that our invention is not limited to any specific style or type of loose leaf binder. In these views the sheets 1, which are ruled and 15 columned to receive the desired data, are placed on the prongs 8 of the binder comprising covers 2 and hinged back sections 2', perforations 3 being formed in the sheets adjacent their upper margin.

These sheets may, for example, be records of 20 the sales made by a particular salesman or department in which case enough sheets for a week or month, or any desired period of time, are arranged in shingled relationship from right to left, showing at the right hand margin the totals of 25

the various entries. Then on each sheet the amounts are totaled at the bottom for each day's sales. Due to the arrangement of the sheets in 30 overlapping relation so that the right hand margins of all sheets are visible at the same time the totals may be read cross-wise and added together

to ascertain the total sales for the period; also any line may be added cross-wise to determine the sales of any certain commodity. When the sheets 35 are arranged in the loose leaf binder they are in sets, each of which is preferably separated from another by an index or dividing sheet. In this manner the records of individual salesmen may be separate. It may, for example, be desired to

remove all of the sheets pertaining to an individual salesman's sales to another department or to ascertain quickly the total business done in a certain article over a period of time. This work 40 is done by placing the sheets on a peg board (not shown). We arrange to do this with the minimum amount of time and without disturbing the sheets in the following manner. We provide a

pair of flat bars 4 and 5. The lower one 4, is provided with a plurality of upright pins 6, which are located so as to enter the holes 3 in the sheets 45 1, when they are vacated by the row of prongs 7, opposite the row of prongs 8, which supports the sheets 1 when the binder is opened.

A plurality of slots 9, are formed in the bar 4. These slots are spaced to register with all of the 50

55

A plurality of slots 9, are formed in the bar 4. These slots are spaced to register with all of the 55

prongs on one bottom section 2' of the loose leaf binder in which the sheets are bound. Preferably the slots 9 are flared as at 10 adjacent the upper edge of the bar 4. This makes it easy for the 5 prongs to enter the slots when the bar is inserted under the sheets 1 as shown in Fig. 2.

The upper bar 5 is now placed on top of the sheets and above the bar 4 clamping the sheets between them holes 6' being provided for the 10 reception of the pins 6 of the lower bar. Pins 11 and 12 are provided in the lower bar. These pins are fitted to holes 13 and 14 formed in the top bar. Holes 9' which register with the slots 9 must be provided in the top bar for the entrance 15 of the prongs 8 thus insuring alinement as the prongs will pass through both bars. It may be found desirable to provide the construction shown in Fig. 11 in which event the holes 9' are not required. Where this is done the construction 20 shown in Fig. 11 is employed in which pins 20 are mounted in the lower bar 4. Each of these pins 20 is provided with a head 21 contacting the under surface of the top bar when it is placed on the lower bar. This operates to space the two bars 25 so as to permit the entrance of prongs 8 through the slots 9. The two bars, 4 and 5 are detachably secured together in any suitable manner. We have shown a type of spring snap button consisting of a plunger 16 and a socket 17 such as are 30 commonly used on automobile curtains and the like. They release with a slight pressure upon the plunger 16. The lower bar is preferably counter-bored as at 15 to permit mounting the fastener without any part thereof projecting beyond the plane of the surface of the lower bar. 35 This is most desirable due to the common practice of placing the bars on a flat desk or the flat inclined surface of a peg board on which the bars slide. If desired the ends 22 and 23 may be bent 40 upwardly as clearly seen in Figs. 7, 8 and 9 to assist in the convenient separation of the two bars.

It will be clear from the foregoing description that when the papers are clamped between the bars 4 and 5 that the entire set of sheets containing the records pertaining to any individual or commodity, may be removed from and replaced in the loose leaf binder without disarrangement of the sheets. Although we have described with some degree of particularity specific details of 45 construction, it is to be understood that it is done only for illustrative purposes and to show a concrete embodiment of our invention. However, we do not wish to be understood as limiting ourselves to such specific details except as such 50 limitation appears in the hereinafter contained claims.

Having described our invention what we regard as new and desire to secure by Letters Patent is:—

1. In a device of the character described to hold 60 a plurality of sheets of paper mounted in shingled relationship, said sheets being provided with a plurality of perforations adjacent one edge; a pair of clamping members, a plurality of pins on one of said members mounted to register with the 65 apertures in the sheets of paper, there being registering apertures in the other member to receive said pins, one of said members having slots extending inwardly from one edge, the other having openings to align with said slots, said slots and 70 openings being adapted to receive the securing means of a loose leaf binder and means to detachably secure said members together.

2. In a device of the character described to hold 75 a plurality of sheets of paper mounted in shingled relationship, said sheets being provided with a

plurality of perforations adjacent one edge; a pair of clamping members, a plurality of pins on one of said members mounted to register with the apertures in the sheets of paper, there being registering apertures in the other member to receive said pins, one of said members having slots extending inwardly from one edge, the other having openings to align with said slots, said slots and openings being adapted to receive the securing means of a loose leaf binder, means to detachably secure 10 said members together, the ends of one of said members being turned up to conveniently separate said members. 5

3. In a device of the character described to hold a plurality of sheets of paper mounted in shingled relationship, said sheets being provided with a plurality of perforations adjacent one edge; a pair of clamping members, a plurality of pins on one of said members mounted to register with the apertures in the sheets of paper, there being registering apertures in the other member to receive said pins, one of said members having slots extending inwardly from one edge, the other having openings to align with said slots, said slots and openings being adapted to receive the securing means of a loose leaf binder, and a push button clamping device at each end of said members. 15

4. In a device of the character described to hold a plurality of sheets of paper mounted in shingled relationship, said sheets being provided with a plurality of perforations adjacent one edge; a pair of clamping members, one of which is shorter than the other, a plurality of pins on one of said members mounted to register with the apertures in the sheets of paper, there being registering apertures in the other member to receive said pins, one of said members having slots extending inwardly from one edge, the other having openings to align with said slots, said slots and openings being adapted to receive the securing means of a loose leaf binder and means to detachably 20 secure said members together. 25

40

5. In a device of the character described to hold a plurality of sheets of paper mounted in shingled relationship, said sheets being provided with a plurality of perforations adjacent one edge; a pair of clamping members, one of which is shorter than the other, a plurality of pins on one of said members mounted to register with the apertures in the sheets of paper, there being pin registering apertures in the other member, there being slots extending inwardly from the edge of one of said members, said slots alternating with said pins and adapted to receive the securing means of a loose leaf binder, there being a push button clamping device mounted adjacent each end of said members, there being apertures in the longer bar to coincide with said slots, whereby said sheets of paper may be inserted in a loose leaf binder. 55

60

6. In a device of the character described to hold a plurality of sheets of paper mounted in shingled relationship, said sheets being provided with a plurality of perforations adjacent one edge; a pair of clamping members, a plurality of pins on one of said members mounted to register with the apertures in the sheets of paper, there being registering apertures in the other member to receive said pins, one of said members having slots extending inwardly from one edge, the other having 65 openings to align with said slots, said slots and openings being adapted to receive the securing means of a loose leaf binder, means to detachably secure said members together, and means to facilitate lifting said members and sheets as a unit, said 70

75

means being adapted to provide convenient means for separating said members.

7. In a device of the character described to hold a plurality of sheets of paper mounted in shingled relationship, said sheets being provided with a plurality of perforations adjacent one edge; a pair of clamping members, a plurality of pins on one of said members mounted to register with the apertures in the sheets of paper, there being register apertures in the other member to receive

said pins, one of said members having slots extending inwardly from one edge, the other having openings to align with said slots, said slots and openings being adapted to receive the securing means of a loose leaf binder, means to detachably secure said members together, said means being so mounted that they will not project beyond the outer surface.
